METHOD OF CONCENTRATING ORES

Alfred H. Leja, Milwaukee, Wis., assignor to A. O. Smith Corporation, Milwaukee, Wis., a corporation of New York

Application January 26, 1938, Serial No. 186,931

5 Claims. (Cl. 209—422)

This invention relates to an improved method of classifying materials and particularly ores in which particles such as gold may be separated on the basis of their heavier specific gravities.

5 It has been customary in concentrating ores to pass a pulp containing finely ground ore over a sluice box or riffle board by means of which the heavier particles are deposited along the riffles while the lighter particles are washed away with 10 the fluid. The principal objection to this process arises from the fact that the original deposit contains a large quantity of said and other lighter particles which are undesirable and which lower the degree of concentration attainable. In the 15 use of rotary bowls equipped with riffles in which concentration is effected by centrifugal force, the same difficulties exist and are possibly of greater magnitude because the centrifugal force throwing the lighter particles into the riffle grooves is 20 greater than gravity. Clogging of the riffles is the undesirable consequence.

It is an object of the present invention to provide a method of concentrating ores making use of apparatus of the type before mentioned, 25 but imparting to the ore deposited along the riffle surface a periodic agitation, effected by a corresponding periodic change of riffle volume, by means of displacement of the riffles, which in the case of the centrifugal bowl, may be either axial, 30 angular or radial.

A further object of the invention is to provide a method of periodically changing the riffle volume by axial, angular and radial riffle displacement during the process of concentration to cause the 35 expulsion of lighter particles deposited in one set of riffle grooves while retaining the heavier ones and collecting in adjacent grooves the heavier particles which are expelled from the first set of grooves until a saturation point for the collection 40 of heavy particles is reached.

A still further object is to improve the concentration by passing the pulp along a riffle surface and periodically imparting a movement to the base of the riffle grooves to agitate the ore deposited and expel lighter, undesirable particles.

Reference is now made to the drawings in which:

Figure 1 is an isometric drawing partly in section, of a riffle board which illustrates the 50 method of applying the present invention;

Fig. 2 is a schematic diagram in section of a rotary type bowl provided with riffles which may be periodically vibrated as herein described;

Fig. 3 is a vertical longitudinal central section 55 of the preferred apparatus for embodying the in-

vention, the riffles being shown in neutral position;

Fig. 4 is a plan view of the apparatus shown in Fig. 3, a portion of the bowl being shown in section, and

Fig. 5 is an enlarged detail sectional view of 5 the riffles in one extreme position of movement, the central portion being broken away.

Referring to Fig. 1, the pulp containing ore to be classified is passed over the sluice box 1 in the direction of the arrow and the ore permitted to 10 deposit in grooves 2 between riffles 3. The riffle surface may be conveniently defined by an apron 4 of rubber or similar material drawn over a number of transverse riffle-forming bars 5 and 5'. Alternate bars 5' are movable relative to 15 stationary bars 5 and are connected to rods 6 arranged in the direction of pulp flow. By reciprocating the rods at periodic intervals alternate grooves will be respectively widened and narrowed, and as a result ore deposited in a 20 groove which is being narrowed will be expelled, while at the same time the next groove in the course of pulp flow will be widened to receive the expelled ore as well as additional ore from the pulp stream. The tendency will be for the heavier 25 particles to stay at the bottom of the groove, while the lighter, undesirable particles such as sand will be gradually worked out of the grooves by repeated reciprocation of the riffles. A higher grade 30 of concentration of heavier particles results from this process.

If the surface illustrated in Fig. 1 be rolled up to provide a sleeve, the same manner of operation may be applied to a bowl type of concentrator. In Fig. 2, a riffle sleeve 7 is drawn over a 35 coil spring 8 placed inside a bowl 9. Pulp is fed through the center of the bowl 10 to the bottom, and when the bowl is rotated the pulp is forced upwardly over the riffle surface and out the top of the bowl. By compressing the spring 8 the width 40 of the riffle grooves will be narrowed, and the particles thrown in the grooves will be agitated. Repeated compression and expansion of the spring re-classes the particles collected in the 45 grooves and perfects concentration.

In Fig. 3, a rotary bowl concentrator is shown which embodies the same principles of operation as that shown in Fig. 1, the details of which are here explained for the purpose of illustration. This precise apparatus is shown and claimed in 50 my co-pending application filed of even date herewith.

The concentrator shown in Fig. 3, consists of a housing 11, enclosing a rotary bowl, the top of the housing having a central opening and an up- 55

wardly projecting hopper 12 into which the pulp is poured at the beginning of and during the concentration operation. Stretched across the opening in the hopper 12 is a screen 13, the opening registering with a funnel portion 14 extending into the bowl and discharging pulp thereto.

The bottom of the bowl is raised in the central portion and a stationary vertical support 15 extends upwardly beneath this portion of the bowl 10 to provide a sleeve for the bowl axle 16. The bowl is mounted on the axle by means of nut 17 which engages washer 18 to hold down the bottom portion 19 of the bowl. The portion of the axle 16 which extends through the bottom 19 is conical 15 and is slotted as at 20 for a locking key. Covering the end of the axle and screwed to a threaded extension thereof is a conical hub cap 21 which spreads the pulp around the bowl and protects the nut 17.

20 The support 15 consists of a vertical sleeve 22 which acts as journal for a pair of bearing cages 23 and 24 carrying suitable roller bearings spaced apart on the axle 16 by a spacer sleeve 25. The axle diameter is increased above the bearing cage 23 to provide a shoulder which bears upon the cage, the lateral surface of the extended portion being enclosed in a ring 26 bolted to the top end of the sleeve 22. Packing 27, disposed within the ring 26, protects this portion of the axle. The 30 ring has an annular depending flange 28 which fits into the upper end of sleeve 22 to position said ring and to retain the outer portion of the cage 23.

The lower bearing cage 24 is retained by a nut 35 engaging a threaded portion at the end of the axle, and a lock washer 30 engages a detent 31 in the end of the axle to lock the nut in position. A plate 32 encloses the lower end of the axle and is bolted to the sleeve 22, a gasket 32' being 40 provided to seal the bearing.

For lubrication of the bearings, oil is pumped through a channel in the wall of the sleeve 22 to the top bearing and allowed to flow down between the axle and sleeve to the lower bearing and out 45 through a central opening in the plate 32. An oil pump may be attached to the system for recirculation of the oil.

The structure just described is supported on a base member 33 disposed beneath a horizontal 50 flange 34 of the sleeve 22 and bolted thereto. The base member is part of a rectangular frame with longitudinal side rails and cross members disposed beneath the bowl and the motor, as shown in Fig. 4.

55 Returning now to the bowl, the bottom portion contains a number of passageways 36, provided with vanes for directing the pulp to the bottom of the riffle chamber, the upper openings of the passageways registering with the end of the funnel 14 in the top of the bowl. This bottom portion is also conical so that the pulp is forced outwardly as well as downwardly to the bottom of the riffle chamber. To protect the metal defining these passages from the force of the outwardly thrown ore, a lining 37 of flexible material such as sand-blast rubber is applied to the outer walls of the passages.

70 The pulp which flows out of the lower end of the passageways 36 enters the bottom of the riffle chamber 38 and is forced outwardly and upwardly by centrifugal force to the top of the bowl. The bottom of the riffle chamber is also protected by a lining 37', a number of thin, vertical vanes 39 holding the same in place and also cooperating 75 with the ring 40 to secure the lower ends of the

riffle sections. There are a number of openings in the bottom of the bowl as at 41 through which the pulp may be flushed into a stationary circular trough 42 mounted on the flange 34. Trough 42 has an inclined bottom and a spout 43 at its lowest portion. When the bowl is rotated no pulp will flow through the openings 41 because of the centrifugal force, but when the riffles are filled and it is desired to clean out the bowl, rotation may be stopped and flushing fluid permitted to 10 enter the riffle chamber through one or more pipes 44 and the concentrates collected beneath the spout 43. Pipe 44 may be provided with holes 44', facing the riffles, through which the flushing fluid may be sprayed.

15 In order to rotate the bowl, there is an extension 45 on the bottom portion of the bowl which serves as a pulley and has slots for a number of V shaped driving belts 46. These belts are driven by a pulley 47 mounted on the vertical shaft of a 20 motor 48 positioned at one side of the bowl.

The bowl is supported by a number of rolls 49 mounted on the base, three such rolls being shown in the present embodiment, spaced around the outer periphery of the bowl. Each roll contacts the bottom portion 50 of the lateral wall 51 of the bowl, and is provided with a rim 52 outside the bowl, for retaining the side wall of the bowl.

Around the outer periphery of the bowl, but 30 located within the wall 51 are a number of vertical studs 53 and 54. Stud 53 shown at the right side of the bowl in Fig. 3 is mounted directly on the bottom of the bowl and held rigidly by a nut engaging the threaded portion extending through the bottom wall of the bowl. In the drawings 24 studs are shown, the number selected depending upon the size of the bowl and the support necessary for the riffle surface. Stud 54 shown at the left side of the bowl is not rigidly mounted to the bottom of the bowl, but is free to move in axial direction with respect thereto. Alternate studs on the bowl are similarly mounted in the manner of studs 53 and 54 respectively, in order that the desired vibration of the riffles may be obtained.

40 Located inside of the riffle chamber is the riffle sleeve 55, the contour of which has been carefully designed to afford the maximum receptive volume for ore concentrates under efficient operating conditions. The upper wall of each riffle groove in the sleeve 55 is horizontal and from the base of the pocket or groove the other wall normally depends inwardly at an angle of approximately 40°. This contour affords optimum 45 riffle surface and also permits reenforcement by 50 spaced metallic members or plates, which impart vibratory motion to the riffles.

It will be noted that the diameter of the riffle wall is smaller at the bottom of the bowl than at the top and to accomplish this the lower rows 60 of riffles are disposed further inwardly than the uppermost rows. The rows might be tapered in a uniform line but that would necessitate the use of supporting plates or rings, each of which would be of different inside diameter. A single offset, 65 as shown in Fig. 3, requires only two sizes of plates, and is less costly to construct.

Referring to studs 53, there are mounted thereon a series of horizontal annular plates 56 spaced apart by sleeves 57, the top and bottom plates 70 being spaced from the top and bottom of the bowl respectively by sleeves which have enlarged end sections 58 for abutment against the top and bottom members of the bowl. Disposed between the plates 56 are a series of annular plates 59 75

mounted on the lateral wall 51 of the bowl, openings 60 being provided in plates 59 through which studs 53 extend. There must be enough clearance for the movement of the plates 59 relative to the studs to impart the full oscillatory-transverse vibration to which these plates may be subjected. Plates 56 and 59 are continuous about the bowl periphery in the form of rings, plates 56 being rigid with respect to the bottom of the bowl, and plates 59 being rigid with respect to the side of the bowl. Plates 56 and 59 are provided with chamfered inner edges 61 which conform to the desired shape of riffle sleeve. The inner ends of the plates contact the riffle sleeve and are to support the same as well as to control the contour of the riffles during vibrations.

The mounting on studs 54 is similar in all respects to that just described on studs 53, except that the plates 59 are rigidly fixed to studs 54, whereas relative to studs 53 axial and radial motion is permitted. Plates 56 will thus engage every other stud around the bowl, while plates 59 will engage alternate studs not engaged by plates 56. In this manner the riffles will be supported by two relatively movable sets of plates which are mounted respectively on alternate studs.

Disposed beneath the bottom plate 59 on studs 54 and between the abutting surfaces of sleeve extension 58 and the bottom of the bowl and engaging studs 53 is an annular, formed spring-ring 62, the purpose of which is to resiliently carry the studs 54, which are not rigidly mounted on the bottom of the bowl. From the method of mounting described it will be seen that the lateral wall of the bowl may be moved in a vertical and horizontal direction while the bottom portion remains fixed in its central bearing support. The spring-ring 62 is of a conventional sinuous form and its annular design serves to maintain the floating studs 54 in proper circumferential position in relation to the bottom of the bowl.

Above the lateral wall 51 of the bowl is an annular member 63, to which the top of the rubber riffle sleeve 55 is attached. The member 63 has an upwardly projecting flange 63', over which the riffle sleeve is drawn, thus providing a higher wall for the riffle chamber. Attached to the top of member 63 and extending over the end of the bowl wall is a horizontal annular plate 64 over which the pulp flows from the bowl. Plate 64 is bolted to member 63 at a number of points, the section of the plate lying on the inside of the bolts engaging the ends of the riffle sleeve to hold down the same. Studs 53, which are rigidly mounted on the bottom of the bowl, are also rigidly attached to member 63, there being a nut 65 engaging the upper end of each stud 53 above the member 63. Studs 54 are not attached to member 63 and are free to move relative thereto, enough clearance being provided above the ends of such studs and below member 63 to permit such motion without interference. Connecting the top ends of all studs is a spring-ring 66, of similar design as spring-ring 62 which engages the lower ends of the studs. Both spring-rings cooperate to resiliently tie the adjustable member to the base member and maintain them in proper circumferential relation at the same time permitting relative axial and radial displacement.

The side wall 67 of the housing 11 is spaced outside the bowl wall to provide a trough 68 for overflowing pulp. In order to protect the metal from particles thrown from the centrifuge the top of the housing and the upper portion of the

side wall is lined with a suitable lining such as sheets of sandblast rubber. The bottom 69 of the trough 68 is inclined and the pulp is permitted to flow downward in a spiral trough to the outlet 70 which is tangential to the bowl. The housing 5 is mounted on the base in any suitable manner, clearance being provided for the V-belt driving the centrifuge, and for easy access to the supporting rolls. It is preferable to make the housing detachable to permit access to the interior of 10 the bowl for inspection or repairs.

Each roll 49 is mounted on a shaft 71, provided with suitable bearings 72. The shaft 71 is supported on a bracket 73 mounted on the frame by means of bolts. Any of the rolls may be elevated by inserting shims 74 between the base of the bracket and the frame 33, but the particular manner of accomplishing this result is immaterial insofar as the scope of this invention is concerned. For instance, the shaft of the rolls 20 might be mounted in a sleeve eccentric therewith, the rotation of which would elevate the center of the rolls.

When the pulp containing finely ground particles of different specific gravity but of fairly 25 uniform size is poured into the rotating centrifugal concentrator the heavier particles in the fluid will be thrown into the riffle grooves, where they will become imbedded. Along with the particles 30 desired to be classified, such as gold, will be particles of sand and the like which are not desired. In a bowl with non-vibratory riffles, particles will become packed in the riffle pockets and clog the same, thereby preventing further classification.

By the invention here disclosed, the walls of 35 the riffle pockets may be contracted and expanded or the base of the groove may be moved inwardly to agitate particles deposited therein and permit improved concentration. When the walls of the riffle are moved toward each other, 40 there will be a pinching effect and a squeezing out of particles, with the heavier particles being retained at the apex of the riffle grooves. Simultaneous with this effect, there will be an expansion of the walls of the adjoining riffles, which 45 expansion will automatically deflect the riffle base toward the bowl center, thereby loosening ore deposited in the groove and permitting more intensive agitation. The total volume of the riffle groove in the last position may be increased, but 50 the depth is decreased, and as a result eddies are caused due to friction with the pulp stream. The pulp which is forced from the groove will be sheared off by the upward flow of fluid and forced into the next higher groove where centrifugal 55 force will again operate to improve the concentration of heavier particles.

This desired agitation may be controlled in the following manner. By elevating two of the rolls 60 and dropping the other roll, the plane defined by the contacting points on the three rolls will be inclined to the horizontal, thus imparting an axial, wobble vibration to the riffle sleeve. This inclination of the bowl cylinder will lift plates 59 mounted on the cylinder as they pass over the raised rolls, and then lower them to the other extreme position as they pass over the depressed roll. Meanwhile plates 56 remain in fixed elevation because of their rigid attachment to the bottom of the bowl by the studs 53. The axis of the 70 studs 53 and 54 will not be parallel in this position, but slightly inclined to each other because of the inclination of the axis of the side wall of the bowl, which carries studs 54, relative to the axis of the bottom of the bowl which carries studs 75

53. The free mounting of alternate studs, such as studs 54, in the manner described, enables the apparatus to assume these changing positions at high speeds of rotation without unduly stressing the members.

5 The centrifugal bowl structure shown in this application is claimed in my copending application 186,930, filed January 26, 1938.

10 The invention having been described what is claimed is:

1. The method of concentrating ores which comprises passing the pulp containing ore to be concentrated along a surface composed of riffles arranged transversely to the flow of pulp, periodically widening and narrowing the grooves between the riffles and collecting the concentrates deposited in the grooves.

2. The method of concentrating ores which comprises passing pulp containing ore to be concentrated along a surface composed of a series of riffles arranged transversely of the direction of the pulp flow, reciprocating alternate riffles periodically in the direction of the pulp flow while the remaining riffles are stationary with respect thereto, and collecting the concentrates deposited in the grooves between the riffles.

3. The method of concentrating ores which comprises passing pulp containing ore to be concentrated along a surface composed of a series of riffles arranged transversely of the direction of the pulp flow, narrowing alternate grooves between riffles periodically to expel a portion of the

ore deposited in the groove, simultaneously widening the remaining grooves periodically to re-classify concentrates collected therein as well as concentrates expelled from adjoining riffle grooves, periodically narrowing the last named grooves while the first named grooves are widened, and collecting the concentrates finally deposited in the grooves between the riffles.

4. The method of concentrating ores which comprises passing the pulp containing the ore to be concentrated over a surface composed of a series of riffles defining riffle grooves arranged transversely of the pulp flow, periodically reciprocating the riffles in the direction of the pulp flow to widen and narrow the riffle grooves and periodically reciprocating the bases of the riffle grooves transverse to the direction of the pulp flow, the latter reciprocation being so timed that the bottom of the riffle groove defines a shallower groove when the riffles are widened by the first named reciprocation and defines a deeper groove when the riffles are narrowed.

5. In the process of concentrating ores by passing the pulp containing the ores along a surface composed of riffles arranged transversely of the direction of pulp flow and collecting concentrates deposited in the grooves between the riffles, periodically varying the width of the grooves a number of times during the process to squeeze out the ore deposited in the grooves.

ALFRED H. LEJA.
